UNITED STATES PATENT OFFICE.

FRANCIS SEYMOUR AND AUGUSTUS BANNIGAN, OF PATERSON, NEW JERSEY; SAID BANNIGAN ASSIGNOR TO SAID SEYMOUR.

SPINNING, DOUBLING, AND TWISTING MACHINE.

SPECIFICATION forming part of Letters Patent No. 242,060, dated May 24, 1881.

Application filed April 27, 1880. (No model.)

To all whom it may concern:

Be it known that we, FRANCIS SEYMOUR and AUGUSTUS BANNIGAN, of Paterson, Passaic county, New Jersey, have invented a new and Improved Spinning, Doubling, and Twisting Machine; and we do hereby declare that the following is a full, clear, and exact description of the same.

Our invention relates to an automatic stop-motion for spinning-machines, whereby the operation of the same is arrested if a thread breaks. It is more particularly an improvement in the class of silk doubling and spinning machinery in which a faller-wire is hung by its eyelet end to the thread, and with the breakage of the latter falls upon the arm of a balance-lever and actuates a detent. In our invention the action of the spinning and doubling devices is arrested when a thread breaks by the depression of a spring-lever, which operates by gravity upon other devices so arranged as to raise or depress the bands of the several spindles, and thus shift them from fast to loose whirls or pulleys. Simultaneously with this operation and result the doubled thread is removed from between the drawing-rolls by the action of the doubling device, which is suitably connected with the band-shifters.

30 The invention consists in the construction, arrangement, and combination of parts, as hereinafter described and claimed.

In accompanying drawings, forming part of this specification, Figure 1 is a front elevation of our improved machine. Fig. 2 is a sectional elevation of the same, showing also the arrangement of the threads in connection with the doubling and twisting devices. Fig. 3 is a plan view of a portion of the machine. Fig. 4 is a perspective view of the band and shifting mechanism. Figs. 5, 6, 7, and 8 are detail views.

The silk filaments or other fibrous material to be operated upon in our improved machine is taken from bobbins placed on the pins *o* of the jack-board *p*, when it is desired to simply double and spin it; but when it is desired to first spin and then double it, and finally respin it thus doubled, the material is taken from the bobbins or spools *a a*. It is unnecessary to

make further reference to the use of the jack-board *p*, it being a well-known feature in spinning-machines, and in this instance subserving no new purpose, nor involving a new mode of operation, since the fibrous material passes from the bobbins held by the pins of the jack-board to the same doubling-eye, and is subsequently acted on in the same manner as the material taken from the bobbins or spools *a a*. Such fibrous material is twisted as it unwinds from the latter, (by means of fliers or other suitable devices, which may be attached to their spindles or otherwise arranged in the usual way,) and passes thence to drag-wires *c c*, around which it is wound; then over the sustaining-rods *d d* at the top of the machine; then down through the fork of the doubling-eye *i*. The two single-twisted threads, thus brought together or doubled, pass between the drawing-rolls *e f*, appearing on the front side of the latter, and passing thence down to the receiving bobbin or spool *a'*; and are simultaneously spun and wound thereon, (its spindle being in practice provided with ordinary appliances for winding on.) The spindles carrying the spools *a a* and *a'* are rotated by bands *m m'*, which are caused to travel at the required speed by the large driving-cylinder *n'*, around which they pass, as shown in Fig. 2. The spindles of the respective bobbins are provided with fast and loose pulleys *a² a³*, Figs. 6, 7—that is to say, with a whirl, *a²*, and loose pulley *a³*. In case of spools *a*, Fig. 7, the fast pulleys or whirls proper, *a²*, are placed below the loose pulleys *a³*, and in the case of spool *a'*, Fig. 6, the fast whirl *a²* is above the loose one *a³*, for a purpose that will presently appear.

Intermediately of the cylinder *n'* and the spindles of spools *a* the bands *m m'* pass over the cylinder *n*, Fig. 2, by which they are prevented from turning or twisting—that is to say, they are held flat on the whirls to facilitate the action of the shifting devices, which we will now describe. As before intimated, we shift the bands from the said fast to the loose whirls, and thereby arrest the rotation of the spools and the operations of doubling and spinning in case a thread breaks. Such arrest of action depends primarily on the position of the piv-

oted fallers or faller-wires *i*. They are pivoted to a bracket, *i*, fixed on the frame of the machine, and their free ends are normally upheld by the tension of the filaments or threads, which is incident to the action of the drawing-rolls *e* and *f*. If a thread breaks under the strain to which it is subjected, the faller-wire through whose eye it passes instantly drops upon one of the lateral arms, *h*³, of an elbow-lever, *h*, Figs. 2 and 4, which is pivoted at the apex of its angle to the frame of the machine. The weight of such faller-wire overcomes the tension of a spiral spring, *g*, and tilts the lever downward into the position shown in dotted lines, Fig. 2. 10 A rod, *p*², is attached to the longer horizontal arm of lever *h* by means of a screw that passes through the vertically-elongated eye of said rod, and the lower end of the latter is pivoted to a link or block, *e*², to whose lateral extremities are pivoted levers *e*', which are fulcrumed on fixed pivots so as to vibrate in a vertical plane. The above-described depression of the lever *h* causes the rod *p*² to carry down the block *e*², and thus simultaneously tilt the levers 15 *e*', thereby elevating their broadened outer ends, *e*³, Fig. 2. In such operation the link *e*² falls upon the middle belt, *m*', and shifts it from the fast whirl *a*² of the spindles, carrying bobbin *a*' down onto the loose pulley or whirl 20 *a*³, and the levers *e*' simultaneously shift the outer belts, *m*, upward onto the loose pulleys *a*³ of the spindles carrying bobbins *a*, thus arresting the spinning and doubling operation, as before stated; but it is obviously necessary 25 to also arrest the action of the drawing-rolls *e* and *f* upon the threads at the same time, and for this purpose we pivot the doubling-eye *i*' to a fixed portion of the machine, and provide it with a lateral arm, which is connected with the 30 rod *p*² by a link, *k*, Figs. 2, 4. It hence results that when the lever *h* and rod *p*² descend, as above described, the tension on link *k* turns the doubling-eye *i*' on its pivot, Fig. 8, and thereby carries the thread laterally out between the portions of rolls *e* and *f* which are in contact into the space beneath the reduced end of the upper roll, *e*, so that it is no longer drawn forward.

In respect to details, it should be stated that 35 the spring *g* is attached to the vertical portion *h*' of lever *h* at a point slightly in rear of its pivotal bearing, whereby the lever is held in the position shown in Figs. 2, 4. The tension of the spring is regulated and the sensitivity of the lever *h* to downward pressure increased or diminished at will by adjusting the lower end of the spring in different notches of a rack-bar, *p*', (shown clearly in Fig. 4,) as will be readily understood.

Instead of adjusting the lower end of the 40 spring along the rack-bar, we may adjust the rack *p*' higher or lower, and to this end the shank of the latter may be slotted, and a screw passed through the slot to secure the device 45 to the frame.

In order to facilitate the action of the lever *h* and render it as rapidly effective as possi-

ble, we cut away the sides of its pivot *h*², as shown in Fig. 5, thus practically providing a knife-edge bearing, on which it is supported 70 and tilted.

In order to vary the pressure between the rolls *e* and *f* as required for threads of different thicknesses, &c., the bearing of the upper roll, *e*, is constructed with a vertical slot, to 75 allow vertical adjustment of the same by means of a thumb-nut, *x*, Fig. 1.

The required vertical traverse of the doubled thread while being wound on the spool *a*' is produced by a cam, *b*, Figs. 1, 2, 6, on shaft 80 *b*', which acts on a projection, *b*³, attached to a bar, *r*, which is adapted for vertical motion and guided by vertical rods *s*.

The whirl *a*² of the spindle of receiving-bobbin *a*' rests on a tube or long collar, *a*⁴, Fig. 6, 85 and is thus held out of contact with the pulley *a*³, which rotates loose on said tube. The latter is secured in the required adjustment by a set-screw, *a*⁶, (shown in Fig. 1,) which passes through the fixed rail *b*⁴. The whirls *a*² of the 90 spindles of feeding-bobbins *a* being below the loose pulleys *a*³, Fig. 7, the latter require to be held up out of contact with the former; hence we secure the tube or collar *a*⁷ immovably in the rail *b*⁵, and provide its lower end with a 95 lateral flange, which is inclosed in a recess in the under side of said whirl. Oil is supplied to both spindles of bobbins *a* and *a*' through holes in tubes *a*⁴ *a*⁷.

The shaft *b*', cylinder *n*, and shaft *b*⁶, on 100 which the drawing-roll *f* is mounted, are suitably geared together so as to revolve at the requisite speed.

What we claim is—

1. The combination of the lever *h*, provided 105 with arm *h*', with the spring *g*, cross-bar *h*³, fallers *i*, rack *p*', connecting-rod *p*², and band-shifters *e*' *e*', substantially as shown and described.

2. The combination, with a pivoted lever 110 adapted to tilt and fall when a thread breaks, and a rod attached thereto, of a link, *e*², and levers *e*', which are pivoted to and extend laterally from the latter, and are suitably fulcrumed to allow vertical vibration, the bands 115 *m* *m*' *m*', cylinder *n*', and the spindles having the whirls and loose pulleys, and adapted to support the supply and receiving bobbins *a* *a*', all arranged as shown and described, whereby the depression of the link raises the outer ends 120 of the levers, and thus carries the middle band downward and the outer bands upward, as specified.

3. The combination, with the bands and band-shifters *e*' *e*', the vertically-tilting lever *h*, and 125 a faller-wire arranged above it, of the connecting-rod *p*², having a slot or elongated eye in its upper end, as shown, for the purpose specified.

4. The forked doubling-eye *i*', pivoted as 130 shown, so as to shift laterally, and provided with a horizontal arm, in combination with the rod *p*² and link *k*, connecting it with the doubling-eye, the vertically-vibrating lever *h*,

band-shifting devices $e' e^2$, and the drawing-rolls, as shown and described.

5. The combination of the sustaining-rods d , arranged at the top of the machine, and the drag-wires $c c$, with the faller-wires i , doubling-eye i' , the drawing-rolls, the spindles adapted to carry the supply and receiving bobbins, and actuating mechanism, as shown and described.

10. 6. The combination of the elbow-lever $h h'$,

pivoted at the apex of its angle, the spring g , attached to its upper end, and a rack-bar, p' , to which said spring is attached, as shown, whereby the tension of the spring may be adjusted, as and for the purpose specified.
